UNITED STATES PATENT OFFICE

2,517,978

ICE BREAKING ATTACHMENT FOR VESSELS

Millard Collier, Vinita, Okla.

Application June 1, 1948, Serial No. 30,272

1 Claim. (Cl. 114—41)

1

This invention relates to ice breakers for ships, and more particularly to an adjustable ice breaking apparatus for attachment to the prow of a vessel.

A main object of the invention is to provide a novel and improved ice breaking attachment for vessels which is simple in construction, easy to install and which is adjustable in accordance with the thickness of the ice crust to be penetrated.

A further object of the invention is to provide an improved ice breaking attachment for ships which is relatively light in weight, very rugged in construction and which is adapted to apply a thrust to the ice crust immediately below the crust forwardly of the prow of a ship to force the crust upwardly and laterally whereby the ice is broken in an efficient manner and with a minimum amount of retardation of the vessel.

Further objects and advantages of the invention will become apparent from the following description and claims, and from the accompanying drawings, wherein:

Figure 1 is a horizontal cross-sectional view taken through the forward portion of the hull of a vessel equipped with an ice breaking attachment constructed in accordance with the present invention.

Figure 2 is a front elevational view of the prow of the vessel of Figure 1, showing the attachment in front view.

Figure 3 is a side elevational view of the forward hull portion of the vessel of Figure 1 showing the ice breaking attachment in side elevation.

Referring to the drawings, 11 designates the conventional forward hull portion of a ship. Secured to the upper prow side portions of the hull are respective elongated plate members 12, 12 and secured to each plate member 12 are the spaced bifurcated brackets 13, 13. Secured to the lower prow side portions approximately at the water line are additional pairs of spaced bifurcated brackets 14, 14. Pivotally secured to each bracket 14 is a forwardly and outwardly extending substantially horizontal bar member 15.

Designated at 16 are inclined bar members respectively secured at their forward ends to the ends of the respective bar members 15, and connected at their rear ends, by means of turn buckles 17, to the respective brackets 13. Secured to the inclined bar members 16 at each side of the prow are a plurality of spaced parallel laterally inclined bar members 18, said bar mem-

2

bers extending laterally beyond the longitudinal vertical side planes of the vessel and being rigidly connected at their outer ends by bar members 19. The inner ends of the bar members 18 are rigidly secured to a forwardly and downwardly inclined heavy angle bar 20 formed at its forward end with a pointed tip 21. By adjustment of the turnbuckles 17 the depth of tip 21 below the water line may be accurately regulated.

10 In operation of the device, the turnbuckles 17 are adjusted so that the breaker tip 21 is immediately beneath the crust of the ice. As the vessel moves forwardly, tip 21 engages beneath the crust and applies an upward concentrated 15 thrust thereto which fractures the crust. The broken ice blocks are then moved upwardly and laterally on the lattice structure defined by the bar members 18 and are finally dumped laterally of the longitudinal vertical side planes of the vessel. A channel is thus cleared for the forward movement of the ships.

It will be noted that the lowermost lattice bars 18 are at approximately the same level as the breaker tip 21. This insures that the broken 25 crust fragments will be moved up on the lattice continuously as the vessel moves forwardly. The spacing between the lattice bars 18 is made relatively close to prevent large blocks of ice from lodging between the lattice bars.

30 While a specific embodiment of an ice breaking attachment for vessels has been disclosed in the foregoing description, it will be understood that various modifications within the spirit of the invention may occur to those skilled in the 35 art. Therefore it is intended that no limitations be placed on the invention except as defined by the scope of the appended claim.

What is claimed is:

An ice breaking attachment for a vessel, comprising a fender to be arranged in advance of the bow of the vessel, said fender tapering forwardly and including vertically inclined frames, each frame including spaced horizontal bars extending longitudinally of the frame, vertically inclined transverse end and intermediate bars rigidly secured to the longitudinal bars, the inner inclined bars of the frame being secured together and extending forwardly beyond the frames and being pointed, plates secured to the opposite sides 50 of the bow near its top, brackets secured to the plates, turn-buckles secured to the brackets and to the rear ends of the vertically inclined intermediate bars, lower brackets secured to the opposite sides of the bow, lower horizontal attaching 55 bars secured to the lowermost longitudinal

bars of the frames and pivotally connected with the lower brackets to swing vertically, the lower horizontal attaching bars of each frame being disposed upon the inner sides of the intermediate incline bars and diverging rearwardly with relation thereto to laterally brace the frame.
